O'Meara
ATTORNEY.

UNITED STATES PATENT OFFICE

ALBERT G. ADAMS, OF LOS ANGELES, CALIFORNIA, ASSIGNOR OF ONE-HALF TO EDWARD K. LINCOLN, OF BLANDFORD, MASSACHUSETTS

RAZOR STROPPER

Application filed June 17, 1929. Serial No. 371,347.

The present invention has relation to a device for stropping safety razor blades.

The general object of my invention is the provision of a device for use in connection with the combined canvas and leather strops generally found in barber shops throughout the country, and which is adapted to hold blades of various sizes and shapes. Another object of the invention is to clamp a razor blade in the device diagonally relative to the length of the strop. A further object is to mount such blade pivotally in order to obtain perfect contact between the blade and strop. Another object is to provide a demountable device which, when taken apart, may fit into a relatively small space. These and the further objects and advantages of my invention are fully set forth in the following description and illustrated in the appended drawings, of which;

Fig. 1 is a plan view showing the structure of my invention applied to a razor strop in position for stropping.

Fig. 2 is an elevation of the device with parts broken away for the sake of clearness, and

Fig. 3 is a fragmentary view illustrating certain elements of the device.

The structure of my invention comprises a U-shaped frame 1, to which is attached a handle 2. In the frame is mounted a pair of shafts 3 and 4, and these shafts are connected for simultaneous rotation in opposite directions by means of a pair of rigidly affixed gear wheels 5 and 6.

Radially projecting from the upper shaft 4 is a clamping member 7, in which a razor blade 8 is firmly held. In order to sharpen a razor blade it is merely required to insert a razor strop through the frame 1, below the shaft 3 and, while holding the strop in the usual, well known manner, to draw the device back and forth over the strop, taking care that the lower shaft 3 is caused to press against the strop all the time. By doing this the clamping member, carrying the blade to be sharpened, is automatically turned over each time the direction of movement is reversed.

It is well known that, in order to obtain

a fine cutting edge, the razor blade should be held diagonally during the stropping operation. In order to accomplish this the clamping member 7 is shown shaped to hold the blade at an angle of about 30% relative to the strop. It is furthermore very important that the blade is caused to bear evenly against the strop during the stropping operation, and this result I attain by mounting the clamping member pivotally in a stud 10, which stud in turn is rigidly secured to the upper shaft 4. The member 7 is shown mounted on a pivot 11 which is fitted to turn within the stud 10, and a pin of the latter is seated in a short groove of the pivot, as best shown in Fig. 3, for the purpose of properly limiting the oscillations of the clamping member.

The razor blade may be clamped in position in any suitable manner, the means shown in the drawings comprising a lever 20, the inner end 20^a of which rides on the inclined surface 7^a of the member 7, thereby pressing the jaws of the member firmly together.

As hereinbefore stated, one of the objects of the invention is to provide a device for use in connection with the large canvas and leather strops used by barbers. Such strops are generally fastened together at one end and provided with some means of suspending the strop. The opposite ends of the strop are as a rule fitted with handles or they are fastened together in one handle. The result is that such strop ordinarily is quite thick and bulky at each end, and that therefore, in order to insert the strop, the lower shaft 3 must be spaced quite a distance away from the bottom of the frame. But this is objectionable because the strop should be held as close as possible to the shaft 3, not only in order to turn the clamping member over, but also in order that the razor blade may not incline downwardly too much relative to the strop during the stropping operation.

In the drawings I have shown a member 22 mounted within the frame 1 and pivoted at 23. This member may be drawn out of the way, as indicated in broken outline in Fig. 2, leaving ample space to insert even the bulkiest of barber strops. And when the member is pushed back into working po-

sition it maintains the strop in the proper position. This member may be made of resilient metal in which case it may be made high enough to press the strop against the shaft 3. It is shown made with a hook 24 adapted to snap under the edge of the frame and thereby to lock the member in position.

The structure of my invention is wide enough to accommodate large barbers razor ¹⁰ straps and long safety razor blades. For this reason it is, when assembled and ready for use, comparatively bulky. It is desirable to reduce the size of the device when not in use, and this may readily be done by unscrewing the handle and detaching the clamping member. For the purpose of such detachment the pin 12 is shown mounted on a ¹⁵ resilient finger piece 13. When this finger piece is lifted the pin is drawn out of engagement with the pivot 11, and the member may be withdrawn. The parts may then be packed in a comparatively small space. Another advantage of the detachable clamping member is, that a plurality of interchangeable clamps ²⁰ may be provided, each clamp being shaped to hold a particular shape of blade, if desired.

From the foregoing description it is seen that I provide means for detachably pivoting a razor blade diagonally relative to a strop, ²⁵ and that I provide means for accommodating my device to wide, thick and bulky strops such as used by barbers who contend, that it is necessary in order to obtain a fine cutting edge, first to strop on canvas and to complete the stropping operation on leather. I do not, however, wish to limit myself to the ³⁰ specific construction shown, but may substitute other mechanical devices which come within the scope of the following claims.

40 I claim:

1. In a razor stropper a bifurcated frame, means pivotally hung in the fork of said frame for holding a razor blade to be sharpened, there being sufficient space between said ⁴⁵ means and the fork bottom to insert bulky razor strops, and a substantially semi-circular member pivoted at one end to the edge of said base and capable of being swung into said space until its other end rests upon the base for the purpose of raising the strop to its correct height.

2. In a razor stropper, a bifurcated frame, means pivotally hung in the fork of said frame for holding a razor blade to be sharpened, there being sufficient space between said ⁵⁵ means and the fork bottom to insert bulky razor strops, and a substantially semi-circular member pivoted at one end to the edge of said base and capable of being swung into said space, said member being provided at its outer edge with locking elements for engagement with the opposite edge of the base.

In testimony whereof I have hereunto affixed my signature.
